HIGH-PRESSURE SPRAY WASHING UNIT

Anthony F. Pingatore, 712 E. 39th St.,
Hibbing, Minn. 55746

Filed July 26, 1967, Ser. No. 8,007

Term of patent 14 years

(Cl. D49—1)

FIGURE 1 is a top plan view of a high-pressure spray washing unit, showing my new design;

FIGURE 2 is a front end elevational view of the same;

FIGURE 3 is a rear end elevational view of the same;

FIGURE 4 is a right end elevational view of the same;

FIGURE 5 is a left end elevational view of the same;
and

FIGURE 6 is a bottom view of the same.

The dominant features of my design reside in the portions shown in full lines, the broken line showing of the electric cord being broken away for convenience of illustration.

The fragmentary broken line showings of the hoses are for illustrative purposes only.

I claim:

The ornamental design for a high-pressure spray washing unit, as shown and described.
